UNITED STATES PATENT OFFICE.

CARL SCHOU, OF HOLTE, DENMARK.

TELEGRAPHIC TRANSMISSION.

1,150,395.

Specification of Letters Patent. Patented Aug. 17, 1915.

Application filed January 12, 1914. Serial No. 811,725.

To all whom it may concern:

Be it known that I, CARL SCHOU, a subject of the King of Denmark, residing at Holte, Denmark, have invented certain new and useful Improvements in and Relating to Telegraphic Transmission, of which the following is a full, clear, and exact description.

The invention relates to an apparatus for the automatic transmission of telegraph signals especially adapted for use in wireless telegraphy, and has for its object to reduce the injurious effect of sparking which the closing and interrupting of the telegraphic currents effect on the contact parts controlling the signaling.

According to the present invention there is provided at least two sets of contact apparatus, each consisting of two contact places arranged in parallel, one of which is actuated by means of a perforated paper slip or the like, and is closed and interrupted in accordance with the signals, whereas the other contact place effects the closing and interrupting of the currents care being taken that the former contact place is closed and interrupted, or in any case interrupted, at such moments when the latter contact place is closed. Sparking is thereby avoided at the former contact place. The latter contact place must be constructed in such a manner that it can stand the formation of sparks. Closing and interrupting of the latter contact place is effected periodically and for this purpose rotating drums or rollers with slip springs may be employed.

An embodiment of the invention is diagrammatically illustrated on the accompanying drawing.

40 The telegraph current is led in through the wire *a* and out through the wire *b*. *c* is a rotating disk of insulating material part of its circumference being provided with a segment *d* of metal, reaching over 45 somewhat less than half of the circumference. Two sets of contact springs *e*, *f* and *g*, *h* are adapted to engage the circumference of the disk and these springs are electrically connected in pairs when they are 50 on the segment *d*, which is of such a length

that a connection between the springs *h* and *e* cannot be established. The contact springs *f* and *g* are connected by means of a wire as shown.

In parallel with the contact place formed by the springs *e* and *f* is a contact place *k*, and in parallel with the contact place formed by the springs *g* and *h* is another contact place *m*. The contact places *k* and *m* are actuated in accordance with the signaling, and in such a manner that the closing and interrupting of the said contact places always take place at such moments as the contact springs in question *e*, *f* or *g*, *h* are electrically connected by means of the segment *d*. The contact places *k* and *m* are controlled most appropriately by means of a perforated paper slip mechanically actuated by means of the shaft of the disk *c*, in order to secure that the above condition as to the moments for closing and interrupting is fulfilled. When the two contact places *m* and *k* are interrupted, no currents will flow from *a* to *b*, the circuit always being interrupted by at least one set of the contact springs *e*, *f* or *g*, *h*. If the contact place *m* be closed when the parts occupy the position shown in the drawing, this is of no consequence to the passage of the current; if, however, the segment *d* connects the contact springs *e* and *f*, the current will flow from *a* to *b* during the time that the segment *d* requires to pass the said contact springs. A dot in the Morse system for instance, will therefore be transmitted. Transmission of a dash is effected through three consecutive contact closings, for example first at the contact place *m*, then at the contact place *k* and then again at the contact place *m*. The contact place *m* may however remain closed during the whole period.

Having thus fully described my invention, I claim as new and desire to secure by Letters Patent:

Apparatus for automatic transmission of telegraph signals, comprising a plurality of contact making elements connected in series, means for conductively connecting and disconnecting the same, whereby contact between at least one pair of the said elements

is interrupted, a contact device including an insulated disk having a metal segment of less than half the circumference of the disk and permanently in multiple with each of the contact places formed at the said elements and means for closing and interrupting contact at the said contact devices in accordance with the telegraph signals at such

moments in which the corresponding contact making elements are conductively connected. 10

In witness whereof, I have subscribed my signature, in the presence of two witnesses.

CARL SCHOU.
